UNITED STATES PATENT OFFICE.

AUGUSTUS SEAVER, OF BOSTON, MASSACHUSETTS, ASSIGNOR OF ONE-HALF
TO CHARLES D. WOOD, OF LINCOLN, RHODE ISLAND.

DESIGN FOR A LAMP-SHADE.

SPECIFICATION forming part of Design No. 23,966, dated January 29, 1895.

Application filed November 2, 1894. Serial No. 527,774. Term of patent 14 years.

To all whom it may concern:

Be it known that I, AUGUSTUS SEAVER, a citizen of the United States, residing at Boston, in the county of Suffolk and State of Massachusetts, have invented and produced a new and original design for Lamp-Shades, of which the following is a specification, reference being had to the accompanying drawings, showing a part thereof.

10 Figure 1 is a front elevation of a lamp-shade showing my design. Fig. 2 is a sectional view of the same.

15 The leading feature of my design consists of a globe-shaped shade open at both ends, having a smooth unbroken exterior surface and provided on its interior with prism-shaped ribs running substantially parallel with each other lengthwise of said shade, the said prism-shaped ribs having their greatest width at a 20 point intermediate of their ends and gradually tapering from said points to said ends.

A is the shade, which is of a general globular shape. On the exterior of the shade are formed the prism-shaped ribs α extending lengthwise of said shade. These ribs are 25 widest at points α' between the ends b , and taper gradually from said points to said ends. The shade is provided with openings at the top and bottom, and has a smooth unbroken exterior surface. 30

What I claim is—

The design for a lamp-shade, substantially as herein shown and described.

In testimony whereof I have signed my name to this specification, in the presence of 35 two subscribing witnesses, this 30th day of October, A. D. 1894.

AUGUSTUS SEAVER.

Witnesses:

A. D. HARRISON,
ROLLIN ABELL.
